CATHODE RAY TUBE MANUFACTURE

John C. Turnbull and Richard D. Faulkner, Lancaster, Pa., assignors to Radio Corporation of America, a corporation of Delaware

Application August 2, 1954, Serial No. 447,250

10 Claims. (Cl. 313—64)

This invention is directed to electron discharge tubes, and more particularly to cathode ray picture tubes used for viewing of television pictures and to the method of manufacturing the same.

The usual television picture tube is one consisting of an evacuated tubular envelope having a large conical or frusto-pyramidal tubular portion, which is closed at its large end by a face plate of glass. The smaller end of the cone normally has fixed thereto a tubular glass portion, which is used as a housing or support for an electron gun. The inner surface of the glass face plate is covered with a phosphor layer known as the fluorescent screen which produces a luminescence when struck by electrons from the electron gun. The electron emission of a cathode in the gun is formed into an electron beam which is brought to a sharp focus on the surface of the fluorescent screen. Normally, magnetic fields are used to scan the electron beam over the surface of the fluorescent screen to form a rectangular shape raster. Incoming video signals are applied between the cathode and control grid of the electron gun to modulate the electron beam so that the luminescence produced on the fluorescent screen varies from point to point and produces a light distribution or picture on the fluorescent screen.

The trend in television tube development is one directed toward larger picture tubes requiring large evacuated containers for housing the large fluorescent screen. One form of large tube development has been that of utilizing metal containers or shells, to which the face plate and the tubular glass gun housing are sealed. The use of metal shells has the advantage of providing greater over-all strength to withstand the high stresses due to atmospheric pressure. Also the use of a metal shell enables the tube to have a greater safety factor in case of implosion. If the metal of the shell can be made sufficiently thin, an added advantage is the fact that metal tubes have inherently less weight than comparable glass tubes.

In making large metal shells, it is desirable to use a minimum amount of metal and one of low cost. The development of large metal shells for television picture tubes has progressed from the use of high chromium content—iron alloys to the use of low cost, low carbon steels, such as SAE 1010 steel, for example. Such low carbon steels are known as iron, mild steel, and cold rolled steel.

Many problems arise in the use of such low carbon steels for the metal shell portion of a television picture tube. Normal processing of a metal tube includes heating the metal shell in air at high temperatures during the formation of the glass-to-metal seals and during annealing of the metal and glass parts. Such processing of low carbon steel tubes results in undesired oxidation or corrosion of the metal surfaces, which produces scaling. The scaling is objectionable, for one thing, because it gives the shell a bad appearance. A more serious objection is that in the process of forming the fluorescent

2

screen, loose scale particles on the inside of the shell fall onto the fluorescent screen and produce holes and tears in the fluorescent layer. Also, during manufacturing, problems of rusting or corrosion of the low carbon steel shell are encountered after bulb washing and phosphor settling which include the use of water.

According to the prior art methods, the problems of metal shell corrosion and rusting with consequent scaling have been overcome by coating the metal shell with vitreous enamel. However, this expedient is not entirely satisfactory for several reasons. The enamel coating is an insulator and therefore will not readily conduct away secondary electrons which leave the fluorescent screen during tube operation and impinge on the shell.

It is not easy to mix conductive material with the enamel constituents to render the enamel coating conductive, so the usual practice is to apply a layer of conductive material such as graphite over the enamel coating, which adds to the manufacturing cost.

Another problem that arises with the employment of a vitreous enamel coating is the difficulty of achieving a mat black surface on the enamel coating to reduce internal light reflections during tube operation and thus not interfere with picture contrast.

Furthermore, the enameling operation itself is costly, and the elimination of such an operation would reduce considerably the cost of manufacturing tubes if some other and simpler method could be devised to afford protection to the metal shell during tube processing and at the same time permit normal desired tube operation. It is therefore an object of this invention to provide a new and improved method of manufacturing a cathode ray tube;

It is another object of this invention to provide a novel metal envelope structure for an electron discharge device;

It is a further object of this invention to provide a new and improved method of processing an envelope portion formed from a readily oxidizable metal;

It is a further object of this invention to provide a new and improved method of manufacturing a metal shell having a surface characterized by its resistance to corrosion, rusting and scaling, is mat black, and electrically conductive;

It is a further object to provide for an electron discharge device a new and improved metal envelope portion having a protective coating which is resistant to corrosion, rusting, and scaling, is mat black, and electrically conductive;

It is a further object to provide a new and improved cathode ray tube including a metal envelope portion having a surface which is resistant to corrosion, rusting, and scaling, and which is mat black and electrically conductive.

The above and related objects are achieved in accordance with this invention by thoroughly cleaning the readily oxidizable metal shell, and sandblasting the interior surface of the shell preparatory to the formation of a protective coating. The sandblasting provides a clean rough surface of bare metal free of surface contaminants, on which a tightly adherent mat black oxide coating will form during later processing steps which includes heating the metal shell during sealing and annealing in air or an oxidizing atmosphere. The oxide coating gives protection to the metal shell during tube processing, will not interfere with tube processing, and enhances finished tube performance.

The single figure shows a partially cut away view in perspective of a television picture tube made in accordance with the invention.

The television picture tube shown consists of a frusto-pyramidal portion 10 closed at its large end by a glass

sheet or face plate 12 and at its smaller end by a glass tubular portion or cone 14, which is flared at one end, as is shown at 16, and is sealed to the metal shell 10. The inner surface of the glass face plate 12 is coated with a fluorescent layer 18 of a phosphor material. The phosphor material is one which upon bombardment by electrons luminesces with a substantially white light.

Within the neck portion 14 of the envelope, there is mounted an electron gun 20 consisting of a source of electrons or cathode electrode 22, mounted behind a control grid 24. Spaced from the grid 24 are accelerating electrodes 26 and 28 for accelerating and forming the electrons emitted from cathode 22 into an electron beam directed at the phosphor screen 18. The electron beam is focussed to a fine spot on the fluorescent screen 18 by a magnetic field produced by a focussing magnet 30 arranged around the neck of the tube. Accelerating electrode 28 is connected by spring spacers 31 to the usual conductive graphite coating on the adjacent inner surface of the tube neck 14, with the conductive coating extended in the direction of screen 18 to make contact with the metal shell 10. Potential is applied to accelerating electrode 28 during tube operation by connecting shell 10 to a source of potential, not shown, by a lead 33. The other electrodes of the tube are also supplied respectively with operating potentials by connecting the electrodes in a conventional way by leads extending outside of the tube through the base 35 and base pins 37.

The details of the gun structure and its operation are well known and do not constitute a part of this invention.

The electron beam, produced by gun 20 during tube operation, is normally scanned in a substantially rectangular raster over the inner surface of the fluorescent screen 18 by magnetic fields produced by coils within a yoke member 32 around the neck 14 of the tube envelope. These scanning coils are conventional and well known.

Incoming television signals are normally applied between control grid 24 and cathode 22 of the electron gun to provide a modulated electron beam. As the modulated beam is scanned over the surface of screen 18, it will produce a pattern of light or picture corresponding to the incoming electrical signals. Since the fluorescent screen is normally insulating, the electrons striking the screen cause secondary electron emission from the screen, and the secondary electrons impinge on the side walls of the tube envelope.

In accordance with this invention the metal shell 10 of a television picture tube is formed of a readily oxidizable corrosive metal such as a low carbon steel. The corrosive metal shell is provided as described below with a mat black protective coating of iron oxide. As shown in Figure 1, the black oxide coating 34 extends over the interior surface of the metal except the areas to which glass portions 12 and 14 are sealed. The coating prevents corrosion of the metal during tube processing. Also, the iron oxide coating 34 does not interfere with normal tube operation. Coating 34, as formed according to the invention, is electrically conductive and thus permits electrical conduction of secondary electrons from the screen 18, through the coating 34, to the metal shell 10, connected by lead 33 to an external source of potential.

The method of applying the protective coating 34 to the interior surface of the metal shell 10 is as follows. First the shell 10 is prepared for reception of the iron oxide coating 34 and an enamel frit in the seal areas by an alkaline degreasing operation to clean the metal shell free of lubricants, rust, and dirt. Next the entire interior surface and the sealing areas of the metal shell are sandblasted, with silica sand or Alundum, for example, to provide a clean rough surface. Sandblasting is continued until there is obtained a uniform dull metallic finish, free of any stains or oxide spots on the entire interior of the metal shell and the sealing areas. This insures a clean bare metal surface to which any iron oxide subsequently formed by the application of heat will firmly adhere, since

it is believed that the presence of any surface contaminants on the metal shell will result in scaling of the subsequent oxide coating. The roughening caused by sandblasting also aids in promoting adherence of the oxide coating, and since the oxide coating to be formed conforms to the surface irregularities, a non-reflective surface will be formed. Sandblasting of the seal areas also provides clean surfaces for the application of vitreous enamel frit. The vitreous enamel frit is preferably applied to the small end of the shell 10, shown generally at 42. The enamel frit may be a mixture, for example, of 100 parts of glass frit mixed with 3 to 6 parts of clay, with water added to give the proper application consistency.

The enamel frit is a sealing aid in sealing the glass cone 15 to the readily oxidizable metal shell 10, and without such sealing aid the metal would over-oxidize at its sealing surfaces and a gas-tight seal would be difficult to make. Enamel frit sprayed onto the shell with a thickness of 4-7 mils is satisfactory for sealing to glass.

The enamel frit is then fired down or glazed, preferably by radio frequency induction heating of the small end 16 of the metal shell locally. Local heating of the small end of the shell 10 is carried out for 3 to 5 minutes at a temperature of about 850 to 950° C., during which process, some slight amount of the desired oxidizing occurs in the vicinity of the fired enamel.

Enamel frit is then applied, by spraying, for example, to the inside sealing areas of the large end of the shell 10, shown generally at 44, to a depth of at least $\frac{1}{2}$ inch below the sealing flange shoulder 46.

The glass cone 16 is then sealed to the enameled small end of the shell 10 at a temperature of about 925 to 1050° C., during which time a slight formation of black oxide occurs adjacent to the seal.

Next, the face plate 12 is sealed to the large end of the shell 10, preferably without prefiring the enamel. This may be accomplished at a sealing temperature of about 925° C. to 1050° C. for about 8-10 minutes, during which time there occurs some formation of black oxide on the shell adjacent to the face plate seal. However, thus far there has been no appreciable black oxide formed on the major inside surface areas of the shell.

If desired, the enameling and sealing steps may be varied somewhat. For example, enamel frit may be applied to each end of the shell and the enamel may then be fired by local heating of each end prior to sealing. Alternatively, the whole shell may be heated uniformly to fire the enamel prior to sealing. However, the preferred method described above has been carried out successfully at a minimum of cost.

The sealed assembly is then transferred to an annealing oven, wherein the face plate and metal shell are maintained at a temperature within the annealing range of the face plate glass, or slightly higher, for about 8 to 10 minutes.

The exact temperature at which annealing is carried out depends on the specific composition of the face plate glass used, and will generally fall in the range of about 425 to 575° C. for commercial high expansion glasses suitable for sealing to low carbon steel shells. Annealing is carried out in air or some other oxidizing atmosphere. During this step, a strongly adherent iron oxide coating is formed on the sandblasted interior surface of the metal shell. The assembly is then cooled down to the ambient temperature.

If desired, the oxide coating may be formed on the shell prior to sealing. As indicated previously, both ends of the metal shell may be enameled by uniformly heating the entire shell to the enameling temperature which is about 850 to 950° C. At this high temperature, the thickness of the oxide coating which is formed is more than adequate but is satisfactory.

Another alternative is to enamel each end of the metal shell by local heating, and then heat the shell uniformly to a temperature preferably of about 500 to

600° C. for about 3-10 minutes to form the oxide coating. A somewhat lower temperature may be used, but consistently good results may be obtained at temperatures substantially below 400° C.

The iron oxide, which is formed on the whole interior surface of the metal shell 10 by heating the shell in air or in an oxidizing atmosphere, has a mat black appearance. This mat black surface reduces internal light reflections which would ordinarily detract from picture contrast during tube operation.

The oxide coating, by virtue of its being tightly adherent to the sandblasted surface of the metal shell, is non-scaling and resistant to rusting, so that bulb washing and formation of the fluorescent screen 18 may be carried out without danger of contaminating the screen. The screen 18 is normally formed by settling the phosphor coating from a suspension of the phosphor in an aqueous solution, which is poured into the envelope through the tubular portion 14 before the gun is sealed in. Using steel or iron for the metal portion of the envelope results in excessive corrosion of the metal surfaces by the solutions used in the screening process. Corrosion of the metal surfaces results in the formation of loose scale, which falls on the phosphor surface and contaminates the phosphor screen 18. The oxide coating, however, on the steel shell interior surface eliminates such corrosion and enables the formation of the phosphor screen without undue difficulty.

The oxide coating, moreover, is electrically conductive, and thus provides sufficient conductivity through the coating to the metal shell to prevent the build up of a charge by secondary electrons which are emitted from the fluorescent screen during the operation. The charge would affect scansion of the beam and distort the picture.

In the specification and claims low carbon steel will be taken to include those ferrous metals known in the art as SAE 1010 steel, mild steel, low carbon steel or cold rolled steel.

What is claimed is:

1. The method of applying a mat black, rust-resistant, non-scaling, electrically conductive coating to the interior of a low carbon steel envelope portion for an electron discharge device, said method comprising removing sufficient metal from the interior surface of said envelope portion to impart a dull metallic finish thereto, sealing a glass face plate and a glass funnel portion to said steel envelope portion to form a composite sealed assembly, annealing said sealed assembly in an oxidizing atmosphere and in the temperature range of about 425-575° C. to form a tightly adherent iron oxide coating on the interior of said steel envelope portion, and cooling said sealed assembly to the ambient temperature, said iron oxide coating being mat black, rust-resistant, non-scaling, and electrically conductive.

2. The method of applying a mat black, rust-resistant, non-scaling, electrically conductive coating to the interior of a low carbon steel envelope portion for an electron discharge device, said method comprising degreasing said steel envelope portion, sandblasting the interior surface of said envelope portion to impart a dull metallic finish thereto, sealing a glass funnel portion to one end of said shell, sealing a glass face plate to another end of said shell to form a composite sealed assembly, annealing said sealed assembly, in an oxidizing atmosphere and in the temperature range of about 425-575° C. to form a tightly adherent iron oxide coating on the interior of said steel envelope portion, and cooling said sealed assembly to the ambient temperature, said iron oxide coating being mat black, rust-resistant, non-scaling and electrically conductive.

3. The method of applying a mat black, rust-resistant, non-scaling, electrically conductive coating to the interior of a low carbon steel shell for an electron discharge device, said shell having a large sealing flange at one end, and a small sealing flange at the other end, said method

comprising degreasing said shell, sandblasting said sealing flanges and the interior surface of said shell to obtain a uniform dull metallic finish, applying vitreous enamel coating to said sealing flanges, sealing a glass funnel to said small sealing flange, sealing a glass face plate to said large sealing flange to form a composite assembly, annealing said sealed assembly in air atmosphere in the temperature range of about 425-575° C. for about 8-10 minutes to produce a tightly adherent iron oxide coating on said sandblasted interior surface, and cooling said assembly to the ambient temperature, said iron oxide coating being mat black, rust-resistant, non-scaling, and electrically conductive.

4. The method of applying a mat black, rust-resistant, non-scaling, electrically conductive coating to the interior of a low carbon steel shell for an electron discharge device, said steel shell comprising a hollow frustum of a cone having a large sealing flange at one end and a small sealing flange at the other end, said method comprising degreasing said shell, sandblasting said sealing flanges and the interior surface of said shell to obtain a uniform dull metallic finish, applying vitreous enamel coating to said sealing flanges, sealing a glass funnel to said small sealing flange, sealing a glass face plate to said large sealing flange to form a composite envelope assembly, transferring said envelope assembly to an oven having an air atmosphere and maintained at a temperature within the range of about 425-575° C., holding said envelope assembly in said oven for about 8-10 minutes to form a tightly adherent iron oxide coating on the interior of said shell, and cooling said envelope assembly to the ambient temperature, said iron oxide coating being mat black, rust-resistant, non-scaling, and electrically conductive.

5. An envelope portion for an electron discharge device comprising a low carbon steel shell and a tightly adherent iron oxide coating on the interior of said shell, said coating being mat black, rust-resistant, non-scaling, and electrically conductive.

6. An electron discharge device comprising an envelope including a low carbon steel shell and a tightly adherent iron oxide coating on the interior surface of said shell, said coating being mat black, rust-resistant, non-scaling, and electrically conductive.

7. An electron discharge device comprising an envelope including a low carbon steel shell substantially in the form of a frustum of a cone, a glass face plate sealed to one end of said shell, a glass funnel sealed to the other end of said shell, and a tightly adherent iron oxide coating on the interior surface of said shell, said coating being mat black, rust-resistant, non-scaling and electrically conductive.

8. An electron discharge device comprising an envelope including a low carbon steel shell having sealing flanges

55 at opposing ends thereof, vitreous enamel coating on each of said sealing flanges, a glass face plate sealed to one of said enamel coated flanges, a tubular gun housing sealed to the other of said enamel coated flanges, and a tightly adherent iron oxide coating on the interior of said shell, said oxide coating being mat black, rust-resistant, non-scaling, and electrically conductive.

9. A cathode-ray tube comprising an envelope including a low carbon steel shell, a glass face plate sealed to one end of said shell, a luminescent phosphor screen on the interior surface of said face plate, a tubular gun housing containing an electron gun for producing and directing an electron beam on said phosphor screen, and a tightly adherent iron oxide coating on the interior surface of said shell, said iron oxide coating being mat black, rust-resistant, non-scaling, and electrically conductive.

10. A cathode-ray tube comprising an envelope including a low carbon steel shell substantially in the form of a frustum of a cone, said shell having a large sealing flange at one end and a small sealing flange at the other

end, vitreous enamel coating sealed to said flanges, a glass face plate sealed to said large sealing flange, a luminescent phosphor screen on the interior surface of said face plate, a glass funnel sealed to said small sealing flange, electron beam producing means within said glass funnel, and a tightly adherent iron oxide coating on the interior surface of said shell, said iron oxide coating being mat black, rust-resistant, non-scaling, and electrically conductive.
